UNITED STATES PATENT OFFICE.

FREDERICK H. MEYERS, OF PHILADELPHIA, PENNSYLVANIA; MARGARET MEYERS ADMINISTRATRIX OF SAID FREDERICK H. MEYERS, DECEASED.

EMERY AND SAND-PAPER MACHINE FOR DRESSING LEATHER.

SPECIFICATION forming part of Letters Patent No. 325,431, dated September 1, 1885.

Application filed January 17, 1885. (No model.)

To all whom it may concern:

Be it known that I, FREDERICK H. MEYERS, of Philadelphia, in the county of Philadelphia and State of Pennsylvania, have invented 5 a new and Improved Emery and Sand-Paper Machine, of which the following is a full, clear, and exact description.

The object of my invention is to provide a new and improved machine for pressing leather 10 or other material against an emery or sand-paper wheel, or any other abrading-wheel, without injuring the said article.

The invention consists in the combination, with an abrading-wheel, of a pivoted lever, 15 devices for moving it toward the wheel, and a cushioned support on the said lever.

Reference is to be had to the accompanying drawings, forming part of this specification, in which similar letters of reference indicate 20 corresponding parts in both the figures.

Figure 1 is a side view of my improved emery and sand-paper machine. Fig. 2 is a cross-sectional elevation of the same on the line $\alpha\alpha$, Fig. 1.

25 The emery - wheel, sand - paper wheel, or other abrading-wheel, A, is rigidly mounted on a shaft, B, journaled in a suitable support, and provided with the fixed and loose belt-pulleys C C'. The wheel A is arranged above 30 an inclined table, D, provided with a longitudinal slot, E, through which a cushion can be passed, which receives and supports the article to be acted upon by the wheel. The said cushion is held on a lever, F, pivoted on 35 an upright, G, and below the lever F a lever, H, is pivoted in an upright, J, one end of the lever H being adapted to act on the lever F, and the other end is connected by a rod, I,

with a foot-lever, K, pivoted on the bottom of the frame of the machine. The cushion is 40 preferably formed of leather, but may be made of any other suitable material. In the machine shown it consists of an endless belt, L, passed over rollers M in frames N N', projecting upward from the lever F, and the frames 45 N' being adapted to swing. It can be held in place to hold the belt taut by a hook, O, pivoted on the lever F.

The article to be acted upon is placed upon the cushion, and the foot-lever K is pressed 50 down, the lever H acting on the lever F and pressing it upward. The cushion is moved up through the slot E, and the article is pressed against the wheel A. The article, resting on a cushion, can give more or less, and is not 55 heated or burned by the wheel.

Having thus described my invention, I claim as new and desire to secure by Letters Patent—

1. The combination, with an abrading-wheel, of the table D, having a slot, E, the lever F, 60 rollers, means, substantially as described, for mounting them on lever F, and an endless belt passed over said rollers, and devices for moving the lever F toward the wheel, substantially as herein shown and described. 65

2. The combination, with the abrading-wheel A, of the lever F, devices for moving it toward the wheel A, the frames N N', the rollers M, the endless belt L, and the hook O, substantially as herein shown and described. 70

Jan. 13, 1885.

FREDERICK H. MEYERS.
